Primary Examiner — Sheryl Lane(74) Attorney, Agent, or Firm — Kacvinsky Daisak Bluni PLLC(57) CLAIM

The ornamental design for a vineyard stake, as shown and described.

DESCRIPTION

FIG. 1 is a front view of our new design;

FIG. 2 is a side view of the design of FIG. 1;

FIG. 3 is a top view of the design of FIG. 1;

FIG. 4 is a bottom view of the design of FIG. 1;

FIG. 5 is a detail view of a portion of the front view of FIG. 1; and,

FIG. 6 is a detail view of a portion of the side view of FIG. 2. The vineyard stake is shown with a symbolic break. All portions between the break lines form no part of the claimed design.
